PUMP OF THE SWASH PLATE TYPE

John B. Hawley, Jr., Charles G. Nathe, John T. Gondek, and Irving Nelson, Minneapolis, Minn., assignors, by mesne assignments, to Northern Pump Company, Minneapolis, Minn., a corporation of Minnesota

Application September 28, 1938, Serial No. 232,112

20 Claims. (Cl. 103—162)

This invention relates to a fluid pump, motor or hydraulic transmission device and particularly to such a device of the kind known as the swash plate type. Such a device comprises a rotating cylinder barrel in which pistons reciprocate, these pistons being movable by a rotating swash plate rotating about the axis of the cylinder barrel but being given a wobble motion by a tilting plate which can be tilted at various angles to the axis of said cylinder barrel.

It is an object of this invention to provide such a device with a novel means of rotating the swash plate including a constant velocity type universal joint.

It is a further object of the invention to provide such a device comprising a novel means for driving the swash plate including a constant velocity type universal joint comprising driving and driven members, a driving shaft and a connection between said driving shaft and said driving member permitting angular movement between the axes of said driving member and shaft but preventing relative movement of said parts perpendicular to the axis of said shaft.

It is another object of the invention to provide such a device comprising a driving shaft, a valve plate and cylinder barrel engaging said valve plate, a swash plate, a tilting plate carrying said swash plate, a universal joint for driving said swash plate from said shaft comprising a driving member and a driven member, means receiving the end thrust of said driving member and resilient means holding said cylinder barrel against said valve plate and holding said driving member against said means.

It is still another object of the invention to provide such a device comprising a driving shaft, a cylinder barrel, a driving member for said cylinder barrel, said driving member surrounding and being splined to said driving shaft.

It is still further an object of the invention to provide such a device comprising a valve plate, a cylinder barrel engaging said valve plate and a swash plate for operating pistons in said cylinder barrel together with a novel form of pump housing including side plates secured to said valve plate and to an end member taking the thrust of said swash plate whereby said side plates are maintained in tension by the reactive forces from said pistons to said swash plate.

It is also an object of the invention to provide such a device having a novel form of pump housing assembled from parts of regular prismatic shape having flat engaging surfaces capable of being ground.

It is still further an object of the invention to provide such a device comprising a swash plate, a tilting plate carrying said swash plate and a retaining ring or snap ring for holding said swash plate in said tilting plate preferably with locking means for said ring.

It is further an object of this invention to provide such a device having a novel form of housing comprising prismatic members including an end member forming the valve plate, another end member taking the thrust of the swash plate, side plates extending between and connected to said end members together with top and bottom plates having flat surfaces engaging surfaces on 10 and secured to said end plates whereby said top and/or bottom plate can be removed to permit full inspection of said pump parts without disturbing the moving parts of the pump or the adjustment or positioning of said end and side members.

These and other objects and advantages of the invention will be fully set forth in the following description made in connection with the accompanying drawings in which like reference characters refer to similar parts throughout the several views and in which:

Fig. 1 is a top plan view of the pump, certain parts being broken away and others shown in horizontal section;

Fig. 2 is a view partly in side elevation but with some parts being broken away and others shown in vertical section;

Fig. 3 is a view in side elevation but some parts being broken away and others shown in vertical section;

Fig. 4 is a central vertical section through a snap or retaining ring used;

Fig. 5 is a perspective view on an enlarged scale of the universal joint and connection thereof 10 with the driving shaft, some parts being broken away and others shown in vertical section;

Fig. 6 is a vertical section taken on line 6—6 of Fig. 2 as indicated by the arrow;

Fig. 7 is a perspective view of a connection 15 block used;

Fig. 8 is a partial central vertical section through the valve plate, cylinder barrel and adjacent parts;

Fig. 9 is a face view of the discharging end 20 of the cylinder barrel;

Fig. 10 is a view similar to Fig. 1 showing a modification;

Fig. 11 is a view in vertical section taken 25 through the trunnion and axis of the tilting plate and showing a modification; and

Fig. 12 is a view partly in side elevation and partly in vertical section.

The device described, disclosed and claimed in this invention is an improvement upon that disclosed and claimed in my pending application S. N. 196,225, filed March 16, 1938.

Referring to the drawings a pump or fluid transmission device of the swash plate type is shown comprising a valve plate 15. Such a valve is a well known element in such a device and comprises oppositely disposed openings 15a. Inlet and discharge conduits 16 are provided and are connected to members 17 and 18 respectively secured to valve plate 15, said members 17 and 18 having annular ribs 17a and 18a seating in annular grooves 15b in valve plate 15 and engaging gaskets in the bottom of said grooves. Members 17 and 18 may be secured to valve plate 15 in any suitable manner and in the embodiment of the invention disclosed they are shown as secured by headed bolts 17b, which bolts are disposed adjacent the corner of members 17 and 18 and are threaded into valve plate 15. Members 17 and 18 each have central openings therethrough for receiving conduit 16, said openings having enlarged outer portions in which are disposed packing members 19 engaged by glands 20, which glands are held tightly against said packing members by the headed studs 21 threaded into members 17 and 19. It will be noted that glands 20 have bores larger in diameter than the outer diameters of conduits 16. With the described construction it will be seen that conduit 16 may have some angular movement relative to members 17 and 18 and valve plate 15. The valve plate 15 has a recess in its inner face in which is secured a bronze plate 15c forming the bearing surface for the cylinder barrel. The valve plate is preferably made of Invar steel. This steel contains nickel and the particular metal used in practice has about $\frac{1}{25}$ the coefficient of expansion of regular steel. Bronze plate 15c is welded onto the face of the valve plate 15. Bearing surface 15c has therein a substantially annular groove 15d which is disposed some distance outwardly radially of openings 15a. Circumferentially spaced holes or passages 15e extend into valve plate 15 from groove 15d and holes or passages 15f intersect the passages 15e and extend to the inner surface of valve plate 15 radially outward of bearing surface 15c and of cylinder barrel 22. A cylinder barrel 22 is provided having a face bearing against the face of bronze portion 15c. Said face of the cylinder barrel has the outlet and inlet openings 22d from the cylinders extending therethrough and some distance radially outward from said openings 22d, said face is provided with a plurality of circumferentially spaced slots 22e which extend outward radially or substantially radially to the edge of said cylinder barrel face. As shown in Fig. 8, the inner ends of slots 22e are so disposed radially as to align with groove 15d. With the described construction it will be seen that the oil pumped may pass from the space surrounding cylinder barrel 22 through the passages 15f and 15e to groove 15d. The oil may then enter the slots 22e and pass outward therethrough to the edge of the cylinder barrel. The said face of cylinder barrel 22 is made of hard steel such as case hardened steel and as stated, this bears against the bronze bearing surface 15c. It is desired that there be a very close and perfect fit between the face of cylinder barrel 22 and the valve plate bearing surface 15c. It is desired however, that a lubricating oil film be pro-

vided between this face and bearing surface. Said cylinder barrel 22 has the usual circumferentially spaced cylinders 22c therein with outlet ports 22d adapted to cooperate in the rotation of said barrel with the openings through the valve plate. Cylinder barrel 22 has a central bore with radially extending recesses therein in which are disposed the head portions 23a of connecting members 23 having stems 23b received in bushings 24 carried in a cylinder barrel driving member 25. Driving member 25 fits about and is splined to the driving shaft 26, said shaft having quite a number of circumferentially spaced splines therein. The valve plate 15 is centrally recessed at its inner side to receive a ball bearing 27 in which is journaled the reduced end of shaft 26, said shaft beyond said bearing having a reduced threaded portion 26b on which is secured a nut 26c preferably of the castle type. Pistons 28 are disposed in the cylinders 22c, the same being illustrated as in the form of hollow cylinders. Said pistons have connected thereto the connecting rods 29 having ball shaped ends held in the split bearing members 30 disposed within pistons 28 and engaged and held therein by the threaded sleeves 31. Rods 28 have their other ends of ball shape and received in bearing members 32 held in circumferentially spaced recesses in a swash plate 33 by threaded sleeves 34. Swash plate 33 is recessed at its rear end to receive a hard bearing plate 35 which bears against a series of bearing rollers 36 which in turn bear against a hard bearing plate 37 carried in a recess in a tilting plate 38. Rollers 36 are carried in a cage or supporting member 39. The bearing plate 35 also has its outer periphery engaging a series of rollers 40 carried in frames 41, said rollers bearing against a hard annular bearing plate 42 received in tilting plate 38. The swash plate 33 is thus rotatably mounted in and carried in tilting plate 38. Said swash plate is provided with a shoulder 33a and a snap ring 43 is adapted to engage said shoulder and a shoulder formed at the inner side of a lip 38a of tilting plate 38. Said ring 43 is adapted to be locked in position by having a movable portion or segment 43a which is tapped to receive a headed screw 44 disposed in tilting plate 38 and manipulatable from the outer edge thereof. Swash plate 33 is driven from shaft 26 through a universal joint comprising a driving member 45 and a driven member 46 connected to or forming part of swash plate 33. This universal joint is of a particular type known as the constant velocity type. Such a universal joint comprises a yoke 45a formed in the driving member 45 and a similar yoke 46a formed in the driven member 46, said yokes having non-concentric intersecting ball races which receive the steel balls 47. In the rotation of the driving and driven parts of the joint these balls roll angularly one-half the distance traversed by the yoke. The driving member 45 surrounds shaft 26 and at its end opposite that carrying yoke 45a is provided with a plurality of longitudinally extending tongues 45b shown as rectangular in plan and vertical cross section. These tongues are received in recesses 48a formed in a member 48 rigidly secured to driving shaft 26. The tongues 45b and recesses 48a are shown as four in number. The recesses 48a have formed therein intermediate the top and bottom thereof annular slots 48b. Segmental members 49 are received in recesses 48a between the tongues 45b and the walls of said recesses, said segmental members having tongues 49a projecting from their curved sides and dis-

posed in the slots or recesses 48b. With this construction it will be seen that there may be some relative movement between members 48 and 45 to bring their axes at an angle to each other. No movement of said members in a direction perpendicular to the axis of shaft 26 however, is permitted. Member 48 is thus driven from shaft 26 to the end of which shown as having the keyway 26a will be connected some suitable driving means. Member 45 is driven from member 48 10 and swash plate 33 is driven from member 45 through the universal joint or by the balls 47. A sleeve 50 surrounds shaft 26 and is slidable thereon, the same having one end engaging the reduced end of members 45. The other end of sleeve 50 is received in a member 51 surrounding and slidable on shaft 26. Sleeve 50 abuts against the end of a recess in member 51 and is prevented from rotation by pins 52 in member 51 entering holes therein. The end of the sleeve 50 engaging member 45 is cut away at portions to accommodate movement of the parts. A coiled compression spring 53 surrounds member 51 having one end engaging the inner side of a flange on said member and having its other end seated in a 25 recess in cylinder barrel 22 and engaging a shoulder 22e formed at the bottom of said recess. Spring 53 thus acts to hold cylinder barrel 22 against valve plate 15 and to hold member 45 in position longitudinally of shaft 26.

Member 48 is journaled in a ball bearing 54 carried in an end plate 55, which bearing takes the endwise thrust of member 48. A novel form of housing for the pump is provided. Members 15 and 55 form end members and a pair of plates 56 of rectangular form in vertical cross section are provided, the same having flat surfaces 56a engaging flat surfaces at the sides of members 15 and 55 respectively. A key member 57 extends into members 15 and 56, said key connecting the same and preventing endwise movement of said members. Bolts 58 are also shown extending in the plates 56 and into valve plate 15. Pins 59 which may be dowel pins, connect plates 56 and end plate 55. With the described construction it will be seen that when the reactive forces caused by the pistons 28 in their pumping action act upon the cylinder barrel and swash plate, these forces will maintain the plates 56 under tension since they tend to separate valve plate 15 and end plate 55. The upper and lower sides of valve plates 56 are formed with flat surfaces which are made flush with the flat surfaces at the top and bottom respectively of valve plate 15 and end plate 55. A top plate 60 is provided engaging the flat surfaces at the tops of members 15, 56 and 55, said plate being secured to said members by headed screws 61. A bottom plate 62 engaging the flat surfaces at the bottoms of members 15, 55 and 56 is provided and secured in place by similar screws. It will thus be seen that members 15, 55 and 56 are members of regular prismatic form having flat major and engaging surfaces which may be ground and accurately fitted together. It will be noted that the present construction eliminates the continuous housing 15 in the structure shown in said pending application with the connections to end members 16 and 17. In the present construction the plates 48 are in effect extended and formed into the plates 56. The present structure is much simpler and has many advantages as will be later pointed out. Top plate 60 has opening 60a substantially centrally thereof which is normally closed by a member 63 having an annular rib

5 seated in an annular groove in plate 60 and bearing on the gasket 64. Plate 63 may receive a closing plug or a connection to an expansion tank.

10 A member 66 is connected to the outer side of end plate 55 by headed screws 67, the same having a portion received in the central bore in plate 55 which carries the bearing 54. Shaft 26 extends through a central opening in member 66, which opening is enlarged at its outer end to receive packing members 68 engaged by the end of a gland 69 having an annular portion entering the opening in member 66 and engaging the packing member 68. Gland 69 is pressed against said packing members by the headed screw 70 passing therethrough and threaded into member 66. The side plates 56 have openings therein for receiving the ball bearing members 71 in which are journaled the trunnions 38b of the tilting plate 38. Said openings in side plates 56 are closed by the plates 72 which will be secured in any suitable manner. Supporting members 74 shown as in the form of angle members are secured to end members 15 and 55 and act to support the device. 15 The tilting plate 38 has a hub 38c at its rear end which is bored to receive the shank of a fork member 75. This fork member has disposed between the flat sides thereof a block 76 through which extends a pin 77 received in the sides of fork 75 and having roller bearings 77a between the same and block 76. Block 76 is connected to a vertically movable rod 78 extending upwardly at one end of the pump through a member 79 which receives packing engaged by a gland 80 secured by the nutted studs 81. Rod 78 has a lower rectangular portion 78a having an opening 78b therein between the flat sides of which fork 75 is disposed. Block 76 has flat top and bottom sides and these are engaged by bearing sleeves 76b mounted on roller bearings 76c surrounding bearing shafts 76d. Shafts 76d are secured at their ends in the sides of portion 78a. As shown in Fig. 12 sleeves 76b are disposed in the openings 78b. Said rectangular portion 78a is guided in guide members 82 disposed at either side thereof and secured to end member 55 by the headed bolts or screws 83. Guide members 82 have portions 82a extending along the sides of rectangular portions engaging the inner side of end member 55. 20 With the present construction it is not necessary to have such a thick end member to contain the cylindrical bore. An opening in plate 62 through which member 78 can be inserted is closed by a plate 85.

25 In Fig. 2 a modified form of holding swash plate is shown in which circumferentially spaced lugs 84 are provided having lips 84a projecting over a shoulder formed on swash plate 33. Said lugs 84 are held in place by bolts 85 extending therethrough and threaded into tilting plate 38.

30 In Fig. 10 a modified form of housing is shown for the parts. Side plates 90 are provided and these extend between the valve plate 15' and the end member 55', which valve plate and end member are widened to extend to the outer sides of the plates 90. The ends of side plates 90 may be ground to fit against the adjacent flat and ground surfaces of members 15' and 55'. To hold the parts in assembled position studs 91 extend through members 15' and 55' and inside of side plates 90, said studs being equipped with nuts 92 at their ends. Side plates 90 are connected to members 15' and 55' by the pins 93 which may be dowel pins.

35 In the construction shown in Fig. 10 the angle

plates 94 forming the feet or supports for the pump housing which are designated 74 in Figs. 1 and 2, are connected to the housing by studs 95 passing therethrough and also passing through end members 15' and 55', said studs being equipped with nuts 96 engaging the vertical flanges on members 94 respectively. The studs 95 adjacent the bottom of the housing serve the same purpose as the studs 91 adjacent the top thereof, all of said studs acting to hold end members 15' and 55' and the side plates 90 in assembled position. Otherwise the construction shown in Fig. 10 is the same as already described.

In Fig. 11 a modified form of housing is shown, the same comprising an integral member 100 having a bottom portion 100a and vertical side portions 100b extending at right angles thereto. The housing 100 therefore, forms a three-sided box rectangular in vertical cross section. Said housing will extend between the valve plate 15' and the end plate 55' shown in Fig. 10 and will have the pins 93 extending thereinto from members 15' and 55'. The side members 100b have circular and counterbored recesses therein disposed about the same horizontal axis and adapted to receive cup members 101 having flanges 101a seating in the counterbored portions of said recesses and secured therein by the headed bolts 102. Cup members 101 carry roller bearings 103 in which are journaled the trunnions 38b of the tilting plate 38. The bolts 91 and 95 which connect the housing to end members 15' and 55' are also shown. A cover plate 104 is provided for the top of housing 100 and secured thereto by the headed bolts 105. A cover plate 106 will be secured to the outer side of one side member 100b by the bolts 107. A similar cover plate 108 secured by bolts 109 extends over the cup 101 on the other vertical portion 100b. Gaskets (not shown) will be provided for plates 106 and 108. Trunnion 38b at one side is shown as having an integral extension 38bb projecting through plate 108 which may be used for the attachment of an indicator or for some stroking mechanism for controlling the tilting plate 38. An oil seal comprising packing washer 110 and retaining rings 111 surrounds trunnion portion 38bb in a recess 108a in plate 108.

With the described structure a very rigid housing is provided and the tilting plate can be assembled in the housing even with the long trunnion 38bb. The cup members 101 will be removed when the tilting plate is placed in the housing from the top thereof. Cup members 101 and bearings 103 can then be assembled. By having the integral projection 38bb a very strong construction is provided for controlling the tilting plate. The construction of housing is very simple and efficient.

In operation, when the device is used as a pump, power will be applied to drive shaft 26 and driving member 38 will be rotated. This member will rotate driving member 45 of the universal joint comprising members 45 and 46. To take care of a misalignment of the axes of shaft 26 and member 48 and the axis of driving member 45 which might be due to faulty assembly if the pump is dismantled and reassembled, the flexible connection between parts 48 and 44 is provided which comprises the tongues 45b and the segmental members 49. This flexible connection will insure that no stress other than simple torque will be applied to driving member 45. Driving member 45 drives the driven member 46 with a constant velocity and swash plate 33 is driven by member

46. The swash plate is given a wobble movement due to its rotation in the tilting plate 38 and the pistons 28 are reciprocated in the cylinders 22c. The pistons move away from valve plate 15 when in alignment with one of the openings therethrough and move toward the valve plate when in alignment with the opening in the opposite side thereof so that suction and discharge are applied to the conduits 16 so that fluid is drawn through one of said conduits and discharged through the other. If the device is used as a motor the fluid will be forced through one of the conduits 16, will operate the pistons and rotate the swash plate so that shaft 26 will be driven. The fluid will pass out at the other conduit 16. The bearings for the trunnions of tilting plate 38 being carried in the side plates, the trunnions will always be centrally positioned in said bearings and said trunnions are easily accessible for mounting thereon a stroke indicator to show the inclination of the tilting and swash plates or some control member for the tilting plate. Access can be had to the trunnions by simply removing the cover plates 72.

The pump housing is quite simple in construction and comprises prismatic members having flat surfaces which may be ground to give accurate contact. In the construction shown in Figs. 1 to 3 the side plates are in tension and act to hold the end members of the housing in position. By using the universal joint of the constant velocity type, the rotation of the swash plate and cylinder barrel are synchronized and they are also synchronized in relation to the rotation of the driving shaft. By this construction the driving shaft can be made integral and extend throughout the pump and through the universal joint. This is very desirable and was not possible with the old type of universal joint previously used in such devices, one form of which was shown in said prior application. The present structure is much simpler and the parts, particularly the driving shaft, are much more easily made. The resilient means comprising spring 53 for holding the driving member 45 and the cylinder barrel in position is a simple and desirable structure. The separate guiding members 82 for the control member of the tilting plate makes a lighter, simpler and more easily made construction than where the control member is guided in a cylindrical bore in one of the housing members.

The inlet and outlet conduits 16 are alternately hot and cold in the normal operation due to the high pressure used on the oil or fluid pumped and great strains are set up in these conduits. As stated, these conduits can have motion relatively to valve plate 15 without moving said valve plate or exerting a distorting force thereon. The least amount of distortion in this valve plate results in a hydraulic unbalancing of the pump and permits oil pressure getting between the valve plate and cylinder barrel. This causes the cylinder barrel to move away from or lift off of the valve plate and thus render the pump inefficient and undependable. It will be noted that the top and bottom cover plates may be removed without disturbing the assembled relation of the end members or side plates of the housing or of any of the moving parts. This is a very desirable construction as full inspection of all of the interior of the pump is permitted without disturbing the moving parts of the pump or the adjustment or positioning of the tension members or side plates. The splined or serrated parts connected to the driving member for the cylinder barrel insures a synchro-

nized drive between shaft 28 and the cylinder barrel.

The construction of the engaging portions of the cylinder barrel and valve plate is novel and important. It is necessary to lubricate the engaging bearing surface of the valve plate and the face of the cylinder barrel. It has been proposed to have radial channels extending through the bearing surface on the valve plate outwardly of groove 15d. In the copending application holes were provided in the bearing surface of the valve plate with channels leading to the bottom portions thereof. It is quite a task to drill these holes and with said construction and the construction of the radial channels there is a tendency for dirt and other foreign material incidental to all hydraulic circuits, to become embedded in the relatively soft material of the valve plate. The valve plate bearing surface as above stated, is made from bronze which is relatively soft while the coating face of the cylinder barrel is quite hard. With the present invention a continuous bearing surface is maintained on the valve plate eliminating the above mentioned holes and radial channels. The present invention uses oil grooves or channels in the cylinder block. This construction has several advantages. The centrifugal force due to the rotation of the cylinder barrel is used to cause a positive circulation of the hydraulic medium or oil outward through the grooves 22e. The oil can enter from around the cylinder barrel through the passages 15f, pass through passages 15e to the annular groove 15d and thence to the grooves 22e. There is thus a forced circulation through these passages which would result in a positive flow of the lubricating hydraulic medium. By providing the passages 15f and 15e an ingress of oil is attained from the space between the pump housing to annular groove 15d. The lubrication therefore, does not depend on leakage from holes such as shown in the previous application nor from radial channels which have been suggested in the prior art. The leakage through these parts becomes extremely minute under conditions of perfect fit between the face of the cylinder barrel and the bearing surface of the valve plate and under conditions of low pressure operation this leakage is often inadequate to properly lubricate and cool the said bearing surface and face. If these engaging surfaces are not lubricated they tend to heat and stick together. With the present construction the desired lubrication can be had no matter how closely the cylinder barrel face engages the bearing surface of the valve plate, while with the previously suggested constructions the lubrication became more inefficient as the engagement between the surfaces became more intimate. With the radial slot construction the oil being viscous does not always have a tendency to move inward radially through the slots or grooves. On the other hand due to the viscosity a film may form at the outer end of the grooves. With the present construction as above indicated, there is no tendency for impurities to embed themselves in the bearing surface of the valve plate.

From the above description it will be seen that I have provided a much improved, simpler, compact and efficient structure of pump or hydraulic transmission device. The parts are easily made and assembled, and are very efficient in operation. Certain parts can be easily and quickly removed for inspection without dismantling the moving and adjusted parts of the pump. The

device has been amply demonstrated in actual practice, found to be very successful and efficient and is being commercially made.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. In a pump construction, a pump housing comprising, end members of normal regular prismatic shape and substantially rectangular in transverse cross section each having opposite flat sides with plane surfaces capable of being ground, an intermediate portion having surfaces engaging said flat surfaces and means connecting said portions with said surfaces in engagement to form a housing substantially rectangular in transverse and longitudinal cross section.

2. A pump or hydraulic transmission device of the swash plate type having in combination, a valve plate having flat sides and flat top and bottom, a housing comprising side plates having flat surfaces engaging said flat sides of said valve plate, keys connecting said side plates and valve plate at said surfaces, a cylinder barrel engaging said valve plate, pistons reciprocable in said barrel, a swash plate connected to said pistons, a tilting plate carrying said swash plate and an end member for said housing secured to said side plates and taking the thrust of said tilting plate whereby the reactive forces on said valve plate and tilting plate from said pistons maintain said side plates under tension.

3. The structure set forth in claim 2, said side plates having their edge faces flush with the top and bottom surfaces of said valve plate respectively and with the top and bottom of said end plate respectively and top and bottom cover plates for said housing secured to said valve plate, side plates and end plates.

4. The structure set forth in claim 2, said side plates having axially aligned openings therein, bearings carried in said openings for receiving the trunnions of said tilting plate and cover plates for said side plates covering said openings.

5. A pump or hydraulic transmission device of the swash plate type having in combination, a swash plate, a driving shaft, a universal joint of the constant velocity type connecting said shaft and swash plate and comprising driving and driven members, a member secured to and surrounding said shaft having a plurality of radially extending recesses therein cylindrical in cross section, said driving member having a plurality of tongues rectangular in radial cross section extending into said recesses respectively, each recess having a groove extending about the cylindrical wall thereof and segmental members at either side of each tongue having their flat sides disposed against the flat sides of said tongues and fitting in said recesses and having ribs fitting in said grooves whereby the axes of said driving member and shaft may be out of alignment but radial movement of said driving member is prevented.

6. A pump or hydraulic transmission device of the swash plate type having in combination, a valve plate having a flat bearing surface with oppositely disposed inlet and exhaust passages extending through said surface and having an annular groove therein radially outward of said

openings, passages leading from said groove through said plate and having outlets at the inner side of said plate radially beyond said bearing surface, a cylinder barrel having a face engaging said bearing surface through which the inlet and outlet openings from the cylinders in said barrel extend, said face having grooves extending outwardly therein beyond said inlet and outlet openings, the inner portions of which align with said groove in said bearing surface.

7. A pump or hydraulic transmission device of the swash plate type having in combination, a valve plate having a flat bearing surface with oppositely disposed inlet and exhaust passages extending through said surface having an annular groove therein radially outward of said openings, a cylinder barrel having a face engaging said bearing surface through which the openings into the cylinders in said barrel extend, said face having circumferentially spaced outwardly extending grooves therein radially outward of said last mentioned openings and extending inwardly to communicate with said annular groove and means for supplying oil to said annular groove whereby the rotation of said cylinder barrel will cause a circulation of oil radially outward through said grooves therein and said face and bearing surface will be lubricated.

8. A pump or hydraulic transmission device of the swash plate type having in combination, a valve plate at one end, an end plate at the opposite end, a housing fitting between said valve plate and end plate and having bottom and side members integral therewith and disposed substantially at right angles thereto and a top plate secured to said side members and closing said housing.

9. In a pump or hydraulic transmission device of the swash type having a frame, a swash plate and a tilting plate carrying the swash plate for operating pistons in a cylinder barrel, the combination of a shaft journaled in said frame, and a universal joint of the constant velocity type connecting said shaft and said swash plate and comprising driving and driven members, said shaft extending integrally through said swash plate, said shaft and driving member of said universal joint having respectively circumferentially spaced interfitting tongues and sockets constructed and arranged to be movable for eliminating strains other than simple torque from said joint, whereby said driving and driven members may maintain their aligned positions.

10. In a pump or hydraulic transmission device of the swash type having a frame, a swash plate and a tilting plate carrying the swash plate for operating pistons in a cylinder barrel, the combination of a shaft journaled in said frame, and a universal joint of the constant velocity type connecting said shaft and said swash plate and comprising driving and driven members, said shaft extending integrally through said swash plate, said shaft and driven member of said universal joint having respectively circumferentially spaced interfitting tongues and sockets constructed and arranged to be permitting relative angular movement of the axes of said parts but preventing radial movement thereof.

11. In a pump or hydraulic transmission device of the swash type having a frame, a swash plate and a tilting plate carrying the swash plate for operating pistons in a cylinder barrel, the combination of a shaft journaled in said frame, a universal joint of the constant velocity type connecting said shaft and said swash plate and

comprising driving and driven members, said shaft extending integrally through said swash plate, a member for driving said universal joint rigidly secured to said shaft and having a plurality of radially extending recesses therein about said shaft, the driving member of said universal joint having portions extending into said recesses and means in said recesses connecting said portions to said last mentioned member and permitting angular movement between the axes of said member and the driving member of said universal joint but preventing movement perpendicular to said axes.

12. In a pump or hydraulic transmission device of the swash plate type having a frame, a driving shaft journaled in said frame, a swash plate surrounding said shaft and a cylinder barrel surrounding and driven from said shaft, the combination of a universal joint of the constant velocity type connecting said shaft and swash plate, said joint comprising driving and driven members, said driving member surrounding said shaft and being movable longitudinally of said shaft, a sleeve longitudinally movable on and surrounding said shaft having one end engaging said driving member and resilient means engaging said cylinder barrel for pressing said sleeve against said driving member and for holding said driving member and cylinder barrel in position.

13. In a pump or hydraulic transmission device of the swash plate type having a frame, a driving shaft journaled in said frame, a swash plate surrounding said shaft and a cylinder barrel surrounding and driven from said shaft, the combination of a universal joint of the constant velocity type connecting said shaft and swash plate, said joint comprising driving and driven members, said driving member surrounding said shaft and movable relatively thereto, a valve plate against which said cylinder barrel engages and resilient means between said driving member and cylinder barrel acting to hold said driving member in place and said barrel against said valve plate.

14. In a pump or hydraulic transmission device of the swash plate type having a cylinder barrel with a flat face, the combination of a valve plate having a flat face engaging said flat face of said cylinder barrel, inlet and outlet conduits secured to said valve plate for conducting fluid therethrough and to said cylinder barrel and means securing said conduits to said valve plate including members relative to which said conduits may move angularly so that angular movement of said conduits is permitted relatively to said valve plate whereby stresses occurring in said conduits and moving the same will not move said valve plate relatively to said cylinder barrel to permit the escape of fluid between said valve plate and cylinder barrel.

15. The structure set forth in claim 14, said means including yielding packing means for said conduits.

16. In a pump or hydraulic transmission device having a rotatable swash plate, a tilting plate in which said swash plate is carried having laterally extending trunnions about which it is movable to various angles to give a variable wobble motion to said swash plate, the combination of a housing in which said trunnions are journaled comprising an end plate having a flat inner surface, a member flexibly secured to said tilting plate and vertically movable in said housing for tilting the same having a lower guiding portion

and separate guide members bolted to said end plate and partially embracing said guiding portion for guiding the same in its vertical movement.

17. The structure set forth in claim 16, said 5 guiding portion being rectangular in cross section and engaging said end plate at one side, said guiding members having portions engaging the opposite side of said rectangular portion.

18. In a pump or hydraulic transmission device of the swash plate type having a barrel with cylinders therein, a tilting plate having a flat annular surface adjacent said barrel, a swash plate carried in said tilting plate having an annular shoulder with a surface in a plane parallel 10 to said surface, a retaining ring within said tilting plate engaging said shoulder for preventing said swash plate from moving out of said tilting plate when said pump is starting up or running with negative pressure in said cylinders 15 and means in said tilting plate for holding said ring in place, said means being disposed wholly at a side of said annular surface remote from said barrel.

19. The structure set forth in claim 18, said 20 25

ring having a radially removable dove-tailed section therein and said last mentioned means comprising a screw extending radially in said tilting plate and threaded into said segment.

20. In a pump or hydraulic transmission device of the swash plate type having a frame, a swash plate and a tilting plate carrying the swash plate for operating pistons in a cylinder barrel, the combination of a shaft journaled in said frame, a universal joint of the constant velocity type connecting said shaft and said swash plate comprising driving and driven members having races, balls movable in said races and means for rotating said driving member from said shaft comprising a second member secured to said shaft, said second member and driving member having relative angular movement but no relative circumferential movement whereby only simple torque strains will be transmitted to said joint and undue strains will not be placed on said races and balls.
